UNITED STATES PATENT OFFICE.

FANNIE WOLF, OF JERSEY CITY, NEW JERSEY.

CABINET.

No. 825,098.

Specification of Letters Patent.

Patented July 3, 1906.

Application filed November 17, 1905. Serial No. 287,813.

To all whom it may concern.

Be it known that I, FANNIE WOLF, a citizen of the United States, and a resident of Jersey City, in the county of Hudson and State of New Jersey, have invented a new and Improved Cabinet, of which the following is a full, clear, and exact description.

This invention relates to improvements in cabinets for use in stores in lieu of shelving, and comprises a plurality of boxes for holding goods of any description, the boxes being arranged in tiers or normally one upon another, the object being to provide a simple means for raising the several boxes in a tier and supporting the box or boxes above the one from which it is desired to remove articles after said box is lowered from those above it.

Another object is to provide a lifting mechanism by means of which the box may be raised to the desired height.

I will describe a cabinet embodying my invention and then point out the novel features in the appended claims.

Reference is to be had to the accompanying drawings, forming a part of this specification, in which similar characters of reference indicate corresponding parts in all the figures.

Figure 1 is an end elevation of a cabinet-casing embodying my invention. Fig. 2 is a front elevation thereof, partly in section. Fig. 3 is a sectional detail showing the suspending means employed. Fig. 4 is a sectional elevation of a lifting-jack employed. Fig. 5 is a cross-section thereof. Fig. 6 is an end elevation, and Fig. 7 is a sectional elevation, thereof.

The cabinet comprises a casing consisting of a top board 1, rear uprights 2, and front uprights 3, the uprights being arranged between adjacent tiers of boxes and serving practically as guides therefor.

Arranged in each section of the cabinet is a series of boxes 4 for containing goods, these several boxes being movable vertically, and resting normally on the upper box is a cover 5, which is also movable vertically. Each box above the lowermost one is provided at its ends both at the front and rear with metal plates 6, each plate having a series of perforations 7 for receiving a hook 8 to hold certain of the boxes in elevated position when it is desired to remove goods from the boxes underneath the suspended boxes, as will be hereinafter described.

As clearly indicated in the drawings, the

front and rear hooks are arranged in pairs and mounted to swing on rods 9, attached to the rear and front uprights 2 3, the hooks of one set of pairs being designed for engagement with the boxes at one side of the standards and uprights, while the other hooks of the pairs are designed for engagement with boxes of adjacent series of boxes, depending, of course, upon the box in a series from 65 which it is desired to remove goods. The upper portions of the hooks in a pair are extended upward above the rod on which they are mounted to swing and on which the hooks are crossed. These upwardly-extended diverging ends are designed to be engaged by lugs 10 on shafts 11, having bearings in the rear and front uprights, the said rods being extended through the front uprights and provided with knobs 12. It will 75 be noted in Fig. 2 that suspending-hooks are also provided for the cover 5 for the uppermost part.

As a means for lifting simultaneously the several boxes in a tier I employ a jack consisting of a casing 13, which is secured to the floor, and operating vertically in the casing is a rack 15, from which brace-rods 16 17 extend to connection with the bottom box, the said braces 16 connecting with the boxes 85 near the rear side, while the braces 17 connect with the boxes near the ends. As here shown, these braces are secured to blocks attached to the rack, and the casing 13 is provided with vertical slots 18, in which the 90 blocks may slide.

Mounted to swing on a shaft supported by lugs 19, extended outward from the casing 13, is a pawl 20 for engaging with the rack, and from the rod 21, connected to the pawl 95 above its pivotal point, are links 22, the lower ends of which have pivotal connection with a foot-lever 23, extended outward to the front of the casing and adapted at its inner end to engage with a tooth of the rack. The 100 pawl 20 may be held yieldingly in engagement with the rack by means of a spring 24, which at one end is attached to the extended portion of the shaft 21 and at the other end to an arm 25 on the rack. As this spring 105 may not be sufficiently strong to move the pawl into engagement with the rack as the operating-lever is released therefrom, I provide a pawl below its pivotal point with a downward extension 26, designed to be engaged by a lug 27 on the inner end of the lever 23. When the outer end of said lever is

forced downward, this lug 27 by engaging with the extension 26 will force the pawl into engagement with the rack. In some instances it may be desired or necessary to im-
5 part two lifting movements to the boxes, and obviously in such case the end of the lever 23 must be released from the lug and lowered, and to prevent the pawl during such lower-
10 ing movement from being disengaged from the rack the lever is provided with an arm 28, which will engage with the outer side of the pawl 20 and hold the same closely in connec-
15 tion with the rack.

In the operation when it is desired to re-
15 move goods from one of the boxes—for instance, the box x , indicated in Fig. 2—the several boxes are to be lifted by operating the jack. Of course in operating the jack the outer end of the lever 23 will be moved
20 outward, disengaging the pawl 20 from the rack. Upon reaching the desired elevation the rods 11 are to be rotated to move the hooks 8 into perforations in the box immediately above the box 6. When at the desired
25 height, the lug 27 by engaging to the portion 26 of the pawl will move the pawl into engage-
ment with the rack, as before described; but upon the reverse or upward movement of the outer end of the foot-lever the jack will be
30 lowered, carrying with it the box or boxes be-
low the one engaged by the hooks. Then when in the desired lowered position the arm 28 will force the pawl 20 into engagement
35 with the rack. Of course when it is desired to remove goods from the uppermost box in a tier the cover 5 will be suspended in the same manner as above described.

In the modification shown in Figs. 6 and 7 the several boxes in a tier above the bottom
40 one are designed to be elevated by means of a rope or cable connecting with a foot-lever. In this instance rods 29 extend along the ends of the boxes, the lower and upper rods having their ends projecting into guide-slots 30, formed in the standards. The several rods
45 29 at each side of a tier of boxes are connected by links 31, and attached to the upper rods at opposite ends of the boxes are yokes 32, from which ropes or cables 33 ex-
50 tend over pulleys 34, supported in the upper portion of the casing, thence over pulleys
35 at the rear top side of the casing, and thence downward to connection with levers
36, pivoted to lugs 37 on the front stand-
55 ards. The opposite levers 36 for a series or tier of boxes are connected by a rod 38, which has link connection 39 with a foot-lever 40, pivoted to a standard 41 and adapted to en-
60 gage at its free end in lowered position in a notch 42, formed in a standard 43. In this modification the hooks 44 are mounted to swing on the rods 29 and are operated by lugs 30 on rods 31, arranged between oppo-
65 site hooks and below the rods 29. In this

construction by a downward pressure on the 65 outer end of the foot-lever 40 the several boxes below the lowermost one and the cover of the upper boxes will be elevated. Then the hooks are to be engaged with the box above that from which it is desired to re-
70 move goods, which may then be lowered.

It is obvious that a cabinet embodying my invention will not only be more ornamental than shelving in a store, but will keep the goods clean or free from dust and dirt and, 75 further, that by the jack mechanism very little power is required for elevating the boxes in a tier.

Having thus described my invention, I claim as new and desire to secure by Letters 80 Patent—

1. A cabinet for the purpose described, comprising a casing, a plurality of superim-
posed receptacles in the casing, swinging 85 hooks for engaging with the receptacles, ro-
tary rods, devices on said rods for engaging the hooks with the receptacles, and means for raising and lowering the receptacles.

2. A cabinet for the purpose described, comprising a casing, a series of boxes ar-
ranged in the casing one upon another, a jack 90 for raising several boxes in series, devices for engaging with boxes designed to be sus-
pended while the box or boxes below the sus-
pended box or boxes are lowered, and a ver-
95 tically-movable cover for the uppermost box.

3. A cabinet comprising a casing, a tier of boxes arranged to move vertically therein, the said boxes having perforations at the 100 ends at the front and rear, swinging hooks for engaging in the perforations of a box, ro-
tary rods, lugs on said rods for moving the hooks into perforations of a box, and a jack for lowering and raising the boxes.

4. A cabinet comprising a casing having 105 front and rear standards, a tier of boxes ar-
ranged in the casing, rods having connection with front and rear standards at the ends of the boxes, hooks mounted to swing on said rods for engaging with the boxes, other rods 110 mounted to turn in the standards, lugs on said other rods for operating the hooks in one direction, and a foot-operated jack for rais-
ing the several boxes in a tier.

5. A cabinet comprising a casing, a plu-
rality of superimposed boxes in the casing 115 separable one from another, means for elevat-
ing the several movable boxes in a tier to-
gether, and means for suspending any de-
sired number of boxes while the other mov-
able boxes are in their lowermost position.

In testimony whereof I have signed my name to this specification in the presence of two subscribing witnesses.

FANNIE WOLF.
